UNITED STATES PATENT OFFICE.

CLARK WOODBURY, FOSTER WOOD, AND ALLEN J. SAWYER, OF OLD TOWN,
MAINE.

TUBULAR LANTERN.

SPECIFICATION forming part of Letters Patent No. 258,520, dated May 23, 1882.

Application filed March 30, 1882. (Model.)

To all whom it may concern:

Be it known that we, CLARK WOODBURY, FOSTER WOOD, and ALLEN J. SAWYER, citizens of the United States, residing at Old 5 Town, in the county of Penobscot and State of Maine, have invented certain new and useful Improvements in Tubular Lanterns; and we do hereby declare that the following is a full, clear, and exact description of the same, reference 10 being had to the annexed drawings, making a part of this specification, and to the letters and figures of reference marked thereon.

Figure 1 of the drawings is a representation of a front elevation, partly in section, of our 15 invention; and Fig. 2, a side elevation of the same, also partly in section, and broken away to show the manner of swinging the globe out.

This invention relates to that class of inventions known as "tubular lanterns," and the object thereof is to provide a simple, cheap, and 20 easily-operated lantern that may be quickly lighted or extinguished and readily cleaned without removing the globe, thereby rendering the said globe less liable to become broken 25 when being cleaned; also, should the globe become broken when the lantern is in use the burner, being securely fastened to the oil-vessel, cannot fall off, and thereby ignite the oil, as is often the case in lanterns of this kind. These 30 objects we attain by the construction substantially as shown in the drawings and herein-after described.

In the accompanying drawings, A represents an oil-vessel of a lantern, provided with an air-chamber, B, over which is fitted the usual plate, C, having attached thereto the burner-cap D, which is held securely in place at all times by means of a flat sprung, a, upon the outer side of the air-chamber engaging with a pin, b, upon 40 the lower portion of the burner-cap. At the sides of the air-chamber B are connected air-tube sections E F, which extend along the top of the oil-vessel and are bent up at their outer ends. To the air-tube section E is suitably hinged a tube, G, and within the upper end of the air-tube section F is seated the lower end of a tube, H. These tubes G H communicate at their upper ends with an upright tube, I, to the lower end of which is suitably hinged the 45 cap K of the globe L. This upright tube I is

open at its lower end to admit the entrance of the air which is conveyed to the air-chamber by means of the tubes G H and air-tube sections E F. At the top, where the upright tubes connect with the tubes G H, is attached the 55 usual bail for carrying or hanging the lantern.

When the lantern is intended to be lighted or extinguished it is taken in the left hand, and a suitable latch, c, which holds the tube H in the air-tube section F, is drawn back with 60 the right, and the weight of the oil-vessel will cause the hinge d, connecting the tube G with the air-tube section E, to open, thereby dropping the burner below the globe, as shown in dotted lines, Fig. 1, thus admitting of the lantern being readily lighted or extinguished without removing any of its parts. Should the lantern be resting upon a table or other support when the latch is released with the 65 right hand, the tubes will be drawn back with 70 the left to the position also indicated by dotted lines.

The tube H, when unlatched, is prevented from lateral displacement by means of a flat yielding guide-plate, e, equal in width to and 75 working in the bore of the said tube. This guide-plate is secured at its lower end in the air-tube section F.

The hinge d, being of the construction shown, will not allow of the oil-vessel dropping farther 80 below the globe than is absolutely necessary to light the wick.

When the globe is to be cleaned the oil-vessel is dropped, as above described, and a fastening, f, upon the globe-cap K is turned so as 85 to allow it to pass through a slot, g, in the plate h upon the lower end of the upright tube I, and thus admit of the globe-cap K, to which is attached by any suitable means the globe L, being swung out, as shown in Fig. 2. By 90 swinging the globe out, as above described, the said globe may be readily cleaned without removing the same from the lantern-frame, thus preventing the globe from becoming broken by being dropped from the hands while 95 in the act of cleaning, as is frequently the case where the said globe is entirely removed from the lantern-frame.

The burner is readily removed for the purpose of inserting a new wick by releasing the 100

flat spring-catch *a* from the pin *b* upon the burner-cap D when the oil-vessel is dropped down below the globe and lifting the said burner out from its position in the air-chamber B.

5 Having now fully described our invention, what we claim as new, and desire to secure by Letters Patent, is—

1. In a tubular lantern, the combination, with the tube G, hinged at its lower end to the 10 stationary tube-section E, of the tube H and stationary tube-section F, the latter being provided with a fastening device for securely locking the tube H to the tube-section F or releasing it therefrom, substantially as and for the 15 purpose set forth.

2. In a tubular lantern, the combination, with the upright tube I, of the cap K, hinged there-

to and carrying the globe L, substantially as and for the purpose specified.

3. In a tubular lantern, the hinged tube G 20 and tube H, in combination with the air-tube sections E F, the latter having a yielding guide-plate, *e*, and suitable means for fastening or releasing the tube H therefrom, substantially as specified.

25

In testimony that we claim the above we have hereunto subscribed our names in the presence of two witnesses.

CLARK WOODBURY.

FOSTER WOOD.

ALLEN J. SAWYER.
